UNITED STATES PATENT OFFICE.

CHARLES S. COX, OF BROOKLYN, NEW YORK.

AUTOMATIC PENCIL-SHARPENER.

SPECIFICATION forming part of Letters Patent No. 691,117, dated January 14, 1902.

Application filed September 13, 1900. Serial No. 29,902. (No model.)

To all whom it may concern:

Be it known that I, CHARLES S. COX, a citizen of the United States, and a resident of New York, borough of Brooklyn, Kings county, State of New York, have invented 5 certain new and useful Improvements in Automatic Pencil-Sharpener, of which the following is a specification, reference being had to the accompanying drawings, forming part 10 thereof.

My invention relates to automatic pencil-sharpener; and it consists in the new and novel construction and combination of parts comprising the same, as hereinafter set forth 15 in detail, and pointed out in the claims, the object of the invention being to provide an improved device of this character that is cheap and simple in construction and effective in operation.

20 In carrying my invention into effect I usually inclose the pencil-sharpener mechanism within a casing or frame of neat and attractive exterior appearance, which is designed to contain a calendar and a pin-tray and locate 25 the same upon a suitable base with an ink-stand, the whole forming an attractive and useful desk ornament.

Referring to the accompanying drawings, 30 Figure 1 is a perspective view of my improved device in one form of the same. Fig. 2 is a vertical cross-section through line 2 2 of Fig. 1, showing the pencil-sharpener mechanism; and Figs. 3 and 4 are detail views to be hereinafter referred to.

35 In said drawings, 1 indicates the outer frame or casing within which the several parts comprising the pencil-sharpener mechanism are contained and supported. This frame or casing is provided with an inner horizontal 40 wall or partition 2, which divides the same into two chambers, in the upper one of which (indicated at 3) the pencil-sharpener is contained and in the lower one (indicated at 4) the mechanism for operating the said pencil- 45 sharpener is contained.

A vertical drive-shaft 5, journaled at its ends in the upper and lower walls of the casing 1, extends through the lower chamber 4 and is provided with a loose gear-wheel 6 and 50 a fast ratchet-wheel 7, mounted thereon, the former resting upon the latter and being pro-

vided with a pawl 8, connected therewith, which is engaged by the ratchet when the latter is rotated, so as to communicate movement to the gear-wheel in one direction. A 55 power-spring 9, connected at one end with a fixed pin 10 on the lower wall of the casing and at its opposite end with the drive-shaft 5, acts when placed under tension and released to rotate the said drive-shaft 5, which 60 latter is provided with a key or handle 11 at its lower projecting end as a means to wind up the spring, and thereby put the same under tension.

The gear-wheel 6 meshes with a pinion 12, 65 which is connected with the lower end of a vertical spindle 13, which latter is loosely supported in bearings in the upper and central walls of the casing 1, so as to be capable of having both a rotary and a vertically sliding or 70 longitudinal movement, the said pinion 12 being supported in engagement with the gear-wheel 6, between two arms 14 14 of the casing 1, and having connection with the spindle 13 in a manner to permit of the vertical movement of the latter by means of a feather 15 on the spindle extending into a corresponding groove or opening in the pinion, as clearly 75 shown in Fig. 3. The spindle 13 is provided with an enlarged body portion 16 between its 80 ends and in a position within the upper chamber 4, which is provided with a conical-shaped pencil-receiving recess therein opening through its upper end, into which recess the cutting edges of two knives 17 17 are adapted 85 to extend through openings in the side walls thereof, the said knives being detachably secured upon the outer wall of the body portion 16, within cut-away seats therein, by means of screws 18 18. 90

A lever 19 is pivotally supported in a position above the gear-wheel 6, between two lugs 20 20 on the under side of the central wall 2, and is yieldingly held in a normal position, with one end 21 bearing against the under 95 side of the spindle-body 16 and holding the same in a raised position and its opposite end 22 engaging with a lug 23 on the upper surface of the gear-wheel 6 and holding the latter against the pressure of the power-spring 100 9. The lever 19 is held in such normal position by means of a coiled spring 24, which is

seated in a pocket in the central wall 2 and presses downwardly against said lever, as shown.

In the operation of my improved device one end of a pencil is inserted into the pocket or recess of the vertically-movable spindle 13 and pressed downwardly until the latter has lowered the engaging end of the lever 19 sufficiently to raise its opposite end from engagement with the lug 23 on the gear-wheel 6, and thereby release the latter and permit it to be rotated under the action of the power-spring 9, which rotation of said gear-wheel causes a rapid and increased number of rotations to the pinion 12 and connecting-spindle 13, and thereby causes the knives carried by the latter to cut away the wood and lead of the pencil and give the latter a desirable point. Before the gear-wheel 6 has completed one revolution, but when nearing the same, a second lug 26 thereon, having an upper inclined or cam surface, is moved beneath the lever 19 and returns the same to its normal position, with one end raising the spindle 13 and its opposite end in position to engage with the lug 23 and stop movement of the gear-wheel and drive-shaft upon the completion of one revolution. The wood and lead shavings produced by the sharpening of the pencil are retained in the upper chamber 3 and prevented from coming in contact with the operating mechanism contained in the lower chamber 4 by the intervening wall 2. As a means to permit of the removal of such shavings a portion of the upper wall of the casing (indicated at 27) is removably secured in position by means of screws 28, as shown.

The lever 19, in the present instance shown and as a means for supporting the same against undue lateral displacement, is provided with a central opening 29, through which the drive-shaft 5 is loosely received, and between such point and its spindle-engaging

end extends between two downwardly-hanging arms 30 30 on the under side of the wall 2. 45

Having thus set forth my invention, what I claim, and desire to secure by Letters Patent of the United States, is—

1. In a device of the character described, the combination, with the frame or casing, of a rotary and longitudinally-movable cutter device, a spring-actuated mechanism, embodying a rotating wheel having a stop thereon, for operating said cutter device, a pivoted lever movably held in a normal position with one end engaging said stop on the rotating wheel and its other end engaging the said cutter device whereby it will be operated by the longitudinal movement of the latter to release said wheel, and means carried by said rotating wheel for engaging with the lever to return the same to its normal position at a certain predetermined time in the rotation of the wheel, for the purpose set forth. 50

2. In a device of the character described, the combination, with the frame or casing, of a rotary and longitudinally-movable spindle carrying a cutter or knife, a spring-actuated mechanism, embodying a rotating wheel having a stop-lug thereon, for operating said spindle, a pivoted lever movably held in a normal position with one end engaging said stop-lug on the rotating wheel and its other end engaging the said spindle whereby it will be operated by the longitudinal movement of the latter to release said wheel, and an inclined or cam surface on said rotating wheel for engaging with the lever to return the same to its normal position at a certain predetermined time in the rotation of the wheel, substantially as and for the purpose set forth. 75

CHARLES S. COX.
